NOSE AND THROAT ATOMIZER

Merrill H. Smith, Athens, Tenn.

Application August 19, 1947, Serial No. 769,389

1 Claim. (Cl. 128—173)

1

This invention relates to a nose and throat atomizer and it consists in the constructions, arrangements and combinations herein described and claimed.

It is a particular object of the invention to provide an atomizer in which a filtered medicated air mist may be sprayed into the nose or mouth of a user.

It is also an object of the invention to provide an atomizer of a portable character of light weight, embodying a non-leaking or spilling feature, permitting it to be safely carried in the pocket of a user.

It is a still further and important object of the invention to provide an atomizer wherein a wick device is employed cooperable with a tube and compressible bulb to effect a very fine atomization of a medication at the discharge end of the tube.

A still further object of the invention is to provide an atomizer of simple construction, of few parts, each of which may be readily dismantled for cleaning purposes.

Additional objects, advantages and features of invention will be apparent from the following description and accompanying drawing wherein

Figure 1 is a side elevation of an atomizer constructed in accordance with my invention.

Figure 2 is a vertical sectional view.

Figure 3 is a cross section on the line 3—3 of Figure 2.

Figure 4 is a cross section on the line 4—4 of Figure 2.

There is illustrated an atomizer generally indicated by the reference character 10, consisting of a compressible bulb 11 and a mixing and spray tube 12, suitably interconnected as will be described.

The bulb 11 has a flat planiform base 13 enabling the atomizer to be positioned in an erect position when desired. The base 13 has an opening 14 formed medially thereof in which there is engaged a tube 15. The tube 15 has a reduced outer bore 16 open to the atmosphere and an inner enlarged bore 17 forming a seat for a ball valve 18. The innermost end of the tube is formed with portions 19 overlying the bore 17 for retaining the ball valve within the latter. The opposite end of the bulb has a collar 20, the latter being firmly engaged about a nipple 21, of a coupling 22. The coupling has a threaded end 23 and an axial passage 24 therethrough.

The combined mixing and discharge tube 12 is interiorly threaded, the threads being complementary to the threads of the end 23. The outer

end of the tube has a slightly reduced mounted end 25 and in the apex thereof a minute jet opening 26 is formed. Within the tube 12 there is loosely disposed a cotton wick 27.

In order to fill the tube 12 and saturate or partly saturate the wick 27 with a desired medicating liquid, it is only necessary to unscrew the tube from the coupling 22, then invert the tube so that the liquid may be poured onto the wick. The tube is then replaced upon the coupling, and the device is in readiness for use. Upon compression of the bulb 11, the valve 18 closes and air is forced through the axial passage 24 into the cotton wick 27. The air passing through the wick forms a concentration at the apex of the tube and by reason of the minute atomizer jet 26, forcibly ejects the air and medicated liquid in proper proportions. The resultant admixture will issue as a fine mist, regardless of whether the bulb is given a normal or violent squeeze.

While I have shown and described a preferred construction this is by way of illustration only, and I consider as my own all such modifications in construction as fairly fall within the scope of the appended claim.

I claim:

An atomizer comprising a compressible bulb having a planiform supporting base, a valved air inlet in said planiform base, said compressible bulb being provided with an open collar, a coupling having a nipple securely fixed in said collar, said coupling having an exteriorly threaded end and an axial bore, a combined mixing and discharge tube having a threaded opening complementary to the threads of said coupling, said tube further having a reduced rounded end forming an apex, a minute jet opening being formed at said apex, and an absorbent wick in said tube adapted to be saturated with a medicinal liquid, air passing through said wick upon compression of the bulb forming a concentration at said apex to effect a discharge of a fine medicated mist through said jet opening.
